(57) **CLAIM**

The ornamental design for a swing training implement for ball game, as shown and described.

DESCRIPTION

FIG. 1 is a front elevational view of a swing training implement for ball game showing my new design;
FIG. 2 is a top plan view thereof;
FIG. 3 is a bottom plan view thereof;
FIG. 4 is a rear elevational view thereof;
FIG. 5 is a left side elevational view thereof;
FIG. 6 is a right side elevational view thereof;
FIG. 7 is a cross-sectional view thereof, taken along the line 7-7 of FIG. 1; and,
FIG. 8 is a perspective view thereof.
